UNITED STATES PATENT OFFICE.

PETER W. GRADY, OF GRAND FORKS, NORTH DAKOTA, ASSIGNOR OF ONE-FOURTH TO CLARA DONAHOE, OF SEATTLE, WASHINGTON.

WRENCH.

Application filed May 26, 1924. Serial No. 715,896.

To all whom it may concern:

Be it known that I, PETER W. GRADY, a citizen of the United States, residing at Grand Forks, in the county of Grand Forks and State of North Dakota, have invented certain new and useful Improvements in Wrenches, of which the following is a specification.

The present invention relates to wrenches especially pipe wrenches and has for an object the provision of a quickly adjustable jaw which may be moved with convenience and facility to adjust the wrench for the accommodation of different sizes of work, at the same time providing a durable wrench which effectively grips the work in correspondence with the pressure applied thereto.

Another object of the invention is to provide a wrench of simple and inexpensive construction which is somewhat flexible to especially adapt the same for use on difficult work and under difficult conditions, one of the jaws therof being bodily movable on a fulcrum to obtain a positive and effective purchase on the work eliminating the possibility of the jaws slipping.

Other objects of the invention will be apparent from the following description of the present preferred form of the invention taken in connection with the accompanying drawings wherein:

Fig. 1 is an elevational view of a wrench constructed in accordance with the present invention;

Fig. 2 is a similar view showing a part of the frame and a part of the stationary jaw broken away to disclose details;

Fig. 3 is a cross sectional view of the wrench taken on the line 3—3 of Fig. 1 and looking in the direction of the arrow;

Fig. 4 is a detail fragmentary side elevational view of a slightly modified form of the invention.

The wrench constituting the present invention consists especially of a loop frame 4 which in the present instance is shown to be of rectangular configuration and has fixedly mounted therein a jaw 5 which constitutes the inner jaw of the wrench. A jaw 6 is floatingly mounted in the frame 4 and constitutes the outer jaw of the wrench. It will be noted that the working ends of the jaws 5 and 6 are curved and have the inner faces thereof equipped with teeth 7 which are

adapted for engagement with the pipe or other work to be gripped between the jaws.

The jaws 5 and 6 are of substantially the same length the latter being slidable through the frame 4 in an apparent manner and also being relatively movable with respect to the inner jaw 5 by means of a handle 8. The outer marginal edge of the outer jaw 6 is impinged by a rib 9 which is formed on the inner face of one of the end walls of the frame 4 near the lower margin of the latter as shown in Fig. 2. Consequently, the jaw 6 may be rocked on the rib 9, the latter serving as a fulcrum when the lower end of the jaw 6 is moved. Movement of the lower end of the jaw 5 is accomplished by the handle 8 the inner end of which latter has a cam head 10 formed thereon which is pivoted to the inner end of the wrench 6. The curved face of the head 10 is engageable with the inner margin of the stationary jaw 5 so that pressure upon the handle 8 will urge the lower end of the jaw 6 outwardly to correspondingly move the outer end of the jaw 6 toward the outer end of the jaw 5 in an obvious manner.

Normally the jaws 5 and 6 are held in spaced relation by a coil spring 11 one end of the latter being mounted in a recess 12 formed in the inner face of the inner jaw 5 while the opposite end engages a socket 13 formed in a guard plate 14. The socket 13 is slidable over serrations 15 formed on the inner face of the outer jaw 6. The spring 12 likewise normally holds the outer jaw 6 in intimate contact with the rib 9. The guard plate 14 is slidably mounted on a detachable post 16 mounted in the jaw and is likewise slidably engaged with a locking element 17 which is also detachably mounted in the inner jaw 5. The locking element 17 in the present instance consists of a cylindrical body the outer end of which is formed to provide a tooth 18 which is engageable in any one of the notches between the serrations 15. Consequently, when the lower end of the jaw 6 is moved outwardly so as to urge the outer end thereof toward the inner jaw 5, the tooth 18 of the locking member 17 will engage one of the recesses or notches between the serrations 15 thereby positively holding the outer jaw 6 from movement.

In use of this device it will be apparent that when pressure of the cam head 10 is re-

leased from the stationary jaw 5 by urging the handle 8 upwardly toward the movable jaw 6, the outer or working end of the latter is moved away from the working end of the stationary jaw 5 by expansion of the spring 11 thereby correspondingly disengaging the tooth 18 from the serrations 15. When in this position, it is manifest that the jaw 6 may be urged through the frame 4 until the desired point of adjustability has been attained. The handle 8 is then urged toward the stationary jaw 5 which causes the cam head 10 to impinge the stationary jaw thereby forcing the inner end of the movable jaw 6 outwardly and the outer end of said jaw inwardly in an apparent manner. This cycle of movement reengages the tooth 18 with the serrations 15 in an apparent manner. When said tooth is engaged with the serrations the movable jaw 6 is locked thereby positively gripping the work between the jaws and preventing slipping of the latter. At no time will the portion of the cam head 10, which impinges against the fixed jaw 5, move inwardly between the jaws further than as shown in Figs. 1 and 2 of the drawings. This is accomplished by reason of the construction and location of the element 17 taken in conjunction with the work interposed between the jaws. Consequently, pressure applied to the lever 8 is transmitted through the cam head 10 to the fixed jaw 5.

If desired an abutment 19 may be slidably mounted on the the jaw 5 in order to hold the jaws 5 and 6 in a predetermined position after the lever 8 has urged the jaw 6 into engagement with the work. In this way, the working ends of the jaws 5 and 6 may be held in fixed engagement with the work without the necessity of holding the handle 8. The inner face of the abutment 19 is beveled to provide a tooth 20 which is adapted to bite into the inner face of the jaw 6. The abutment 19, when not in use, is arranged in close proximity to the frame 4 and in view of the fact that the inner face thereof is beveled, the movable body 6 may be urged through the frame without contact with the abutment. When the jaws have

been engaged with the work and it desired to hold said jaws fixed the abutment is then moved on the shank of the jaw 5 away from the frame 4 until the tooth 20 of the abutment engages the inner face of the movable jaw 6.

The above description embodies the essential features of construction and operation of this invention but it is to be understood that various changes may be made in this device especially in the details of construction, proportion and arrangement of parts within the scope of the claims hereto appended.

What is claimed is:—

1. A wrench including a tubular frame equipped with jaws mounted therein one of which is movable and the other stationary, a rib formed on the inner face of one of the walls of the frame, a spring normally forcing said movable jaw against the rib, and a handle pivotally mounted on said movable jaw and engageable with the stationary jaw to rock the movable jaw on said rib against the resistance of the spring.

2. A wrench including a frame, a pair of jaws mounted in said frame one of which is movable in and the other fixed to the frame, a spring to normally hold the movable jaw spaced from the stationary jaw, a handle to urge the working end of the movable jaw toward the working end of the stationary jaw, and a tooth carried by the stationary jaw and engageable with the movable jaw to lock the latter from sliding movement in the frame.

3. A wrench including a frame, a pair of jaws mounted in the frame one of which is movable, means mounted in said frame to hold the sliding jaw spaced from the other jaw, a rib mounted in said frame and engageable with said sliding jaw, a handle for rocking said sliding jaw on said rib against the resistance of said means, and a tooth detachably mounted in said stationary jaw and engageable with the movable jaw when the latter is rocked on said rib to hold the movable jaw from sliding action.

In testimony whereof I affix my seal.

PETER W. GRADY.
